UNITED STATES PATENT OFFICE.

DWAYNE G. YOUNG, OF SEATTLE, WASHINGTON.

METHOD OF COLLAPSING TIN CANS FOR SHIPMENT.

1,273,306.

Specification of Letters Patent. Patented July 23, 1918.

Application filed April 23, 1918. Serial No. 230,364.

To all whom it may concern:

Be it known that I, DWAYNE G. YOUNG, citizen of the United States, residing at Seattle, in the county of King and State 5 of Washington, have invented a certain new and useful Improvement in Methods of Collapsing Tin Cans for Shipment, of which the following is a specification.

My invention relates to improvements in 10 the method of collapsing tin cans for shipment and to improvements in the method of opening such cans prior to collapsing them and the object of my invention is to provide a method by which the opening and collapsing of the cans may be quickly and 15 easily carried out and by which the cans will not be mutilated in a manner detrimental to their future use and may be collapsed into a compact form whereby they may be 20 baled for shipment.

My method of opening and collapsing a can has proven a particularly advantageous method of handling large rectangular shaped tin cans of the form commonly employed as containers for soy bean oil which 25 cans are shipped in large quantities from China and Japan to the western coast of the United States and there emptied.

After these cans are emptied they are collapsed and then baled for shipment back to 30 Japan and China where the tin is used in different building construction.

For this reason it is desired that the cans be opened along lines that will not mutilate 35 them seriously and impair their future usefulness for the purpose of making roofs and at the same time along lines that will permit them to be easily collapsed so that they will occupy the least possible space and 40 be the most compact when baled for shipment.

I accomplish these objects by methods illustrated in the accompanying drawings, wherein—

Figure 1 is a view in perspective of a 45 rectangular can showing the lines along which the ends of said can are to be cut;

Fig. 2 is a view in longitudinal section of a can showing the ends folded inwardly prior to collapsing said can;

Fig. 3 is a view in perspective illustrating a can in a partially collapsed condition;

Fig. 4 is a view in longitudinal section of a completely collapsed can.

Copies of this patent may be obtained for five cents each, by addressing the "Commissioner of Patents, Washington, D. C."

Like reference numerals indicate like 55 parts throughout the several views of the accompanying drawings.

In carrying out my method the ends 5 and 6 of a rectangularly shaped can 7 are each cut along three of the sides as indicated by the broken lines 8, 9 and 10 in Fig. 1 and are bent inwardly against the sides of the can as indicated in Fig. 2. The can may then be crushed as shown in Fig. 3 into the flattened shape shown in Fig. 4. 65

When handling cans that are full of oil the way of procedure to carry out the several operations which constitute my method is to cut one end of the can first, then emptying the can and then cut the other end 70 after the can is emptied.

The two ends of the can shown in Figs. 2 and 4 are cut in such manner that they will fold against the opposite sides of the can but it will be understood that these 75 two ends may be cut so that they will fold against the same side or so that they will fold against sides at right angles to each other if desired.

By the use of my method hereinbefore 80 described the cans are cut along lines that permit the entire ends to be folded against the inside of the cans thereby insuring a compact folding of the cans when they are crushed for baling. The ends of the cans 85 are also preserved as rectangular sheets of tin without being cut or bent in any manner that detracts from their usefulness when they are employed for making toys, etc.

What I claim is:

1. The method of collapsing a rectangular can which consists in cutting the two ends around the edges of three sides thereof, then bending the ends inwardly against the sides of the can and then crushing the 95 can into a flat form.

2. The method of collapsing a rectangular can into a flat form for shipment which consists in cutting one end of said can around the edge of three sides thereof, turning 100 said end so severed inwardly, cutting the other end of said can around the edge of three sides thereof, turning the said other end so severed inwardly and then pressing said can into a flat form.

In witness whereof, I hereunto subscribe my name this 17th day of April, A. D. 1918.
DWAYNE G. YOUNG.
